(No Model.)

H. J. UPTHEGROVE.
COAT OR LIKE GARMENT.

No. 422,669.

Patented Mar. 4, 1890.

UNITED STATES PATENT OFFICE.

HUDSON J. UPTHEGROVE, OF VALPARAISO, INDIANA.

COAT OR LIKE GARMENT.

SPECIFICATION forming part of Letters Patent No. 422,669, dated March 4, 1890.

Application filed December 9, 1889. Serial No. 333,020. (No model.)

To all whom it may concern:

Be it known that I, HUDSON J. UPTHEGROVE, a citizen of the United States, residing at Valparaiso, in the county of Porter and State 5 of Indiana, have invented certain new and useful Improvements in Wearing-Apparel; and I do hereby declare the following to be a full, clear, and exact description of the invention, such as will enable others skilled in 10 the art to which it appertains to make and use the same.

My invention relates to wearing-apparel, such as coats or other similar top garments; and it consists in a garment provided with 15 two crescent-shaped pieces of flexible material or fabric which are stitched to each other along their convex edges and are afterward stitched along their concave edges to the material of the body of the garment under the 20 armpits, and stitched also to the under curve of the sleeve edge at its inner end, as herein-after described and claimed.

The annexed drawings, to which reference is made, fully illustrate my invention, in 25 which—

Figure 1 represents a front view of a coat, showing my improvement applied thereto. Fig. 2 is a detail view of one arm elevated and a portion of the body of a coat, and showing 30 my device extended. Fig. 3 is a plan view of one of the interposing pieces in blank form, and Fig. 4 represents a detail vertical section view of my device.

Referring by letter to the accompanying 35 drawings, A designates a coat or other upper garment consisting of the usual body portion *a* and the sleeves *b*.

B indicates an extensible and collapsible 40 piece which is interposed between the sleeve *b* and the body *a* of the garment. This device I make in two parts *c* and *d*, which are

cut in crescent shape, as shown in Fig. 3 of the drawings annexed, and which pieces are stitched to one another, as at *e*, Fig. 4, and the inner edges *f* being sewed to the arm or 45 sleeve and body *a*, respectively, as shown at *g* and *h*, thus presenting a V-shaped piece in cross-section, which is capable of being extended and contracted, according to the movement of the wearer's arm. This device, it 50 will be seen from the above description and by reference to the drawings, is designed to give ease and comfort to the wearer when in the act of raising the arm, and it is especially adapted to garments worn by sportsmen in 55 raising the fowling-piece to the shoulder, thus relieving the arm of weight, which may be in the pockets of the garment. It is also well adapted for garments of the laborer, as well as others who find it necessary to elevate their 60 arms while at work, and can be readily applied to overalls and the like. At the same time it is durable and cheap to manufacture.

Having described my invention, what I claim, and desire to secure by Letters Patent, 65 is—

The combination, with a coat or other similar outer garment cut away under the arms, of two crescent-shaped pieces of flexible fabric stitched to each other along their convex 70 edges, and stitched along their concave edges to the material of the body of the garment under the arms and to the under curve of the sleeve end adjacent to the armholes of the garment, substantially as specified. 75

In testimony whereof I affix my signature in presence of two witnesses.

HUDSON J. UPTHEGROVE.

Witnesses:

A. D. BARTHOLOMEW,
H. A. GILLETT.
